(57) CLAIM

The ornamental design for a thermo-insulative ice cream container, as shown and described.

DESCRIPTION

FIG. 1 is a top plan view with the cover removed from container of a thermo-insulative ice cream container showing my new design;

FIG. 2 is a bottom plan view thereof;

FIG. 3 is a front elevational view thereof;

FIG. 4 is a rear elevational view thereof;

FIG. 5 is a side elevational view thereof;

FIG. 6 is a perspective view thereof; and,
FIG. 7 is a perspective view of the present invention showing the cover placed on container.

The indicia shown in broken lines is for illustrative purposes only and forms no part of the claimed design.
